UNITED STATES PATENT OFFICE.

HORACE THOMPSON SWASEY, OF TRENTON, NEW JERSEY.

SPREADER.

1,426,423.

Specification of Letters Patent. Patented Aug. 22, 1922.

Application filed January 12, 1921. Serial No. 436,854.

To all whom it may concern:

Be it known that I, HORACE T. SWASEY, a citizen of the United States, and a resident of Trenton, in the county of Mercer and State of New Jersey, have invented a certain new and useful Improvement in Spreaders, of which the following is a specification.

This invention relates to building construction, and more particularly to an improved device for use in building concrete walls, in order that the same may be made of uniform thickness and thus kept straight and plumb with the opposite faces thereof parallel to each other and perpendicular to the base of the wall.

Specifically, it is the object of the invention to provide an improved collapsible extension spreader designed to be placed between the panels, or walls of a mold and between which the concrete or cement mixture is to be poured, to subsequently harden, the spreader being designed to fit between the panels in order to hold them in uniform spaced relation while at the same time being adjustable, to suit molds of different widths depending upon the thickness of the wall to be produced and being capable of convenient and positive adjustment within a wide range, and also being capable of being readily collapsed from an extended position so as to be removed from operative position, to permit continued pouring and formation of the wall.

A further object of the invention is to provide an improved means in connection with the collapsible extension spreader, to temporarily secure the same between two false walls or sides of a concrete form or mold between which the concrete or cement is poured to form the wall, such means facilitating the collapsing of the spreader in addition to the adjustment or extension thereof to properly engage the inner faces of the walls or sides of the form or mold, the device serving to hold the form in proper position and being easy to remove, whether the wall is reinforced with steel rods or the like or not and the devices being then repositioned at a higher elevation and the form or mold being subsequently taken down after the concrete has set, the spreaders having been previously removed.

Other and further objects of my invention will become readily apparent to persons skilled in the art, from a consideration of

the following description when taken in conjunction with the accompanying drawings, wherein:

Figure 1 is a side elevation of the improved collapsible extension spreader for concrete walls in applied position, the mold and wall being shown in section and the spreader being shown in dotted lines in a released position. 60

Figure 2 is a plan view of the structure shown in Figure 1. 65

Figure 3 is a rear elevation or opposite side view from that shown in Figure 1, the mold and wall being also illustrated in section. 70

Figure 4 is a fragmentary perspective view of two pivotally connected sections of the spreader. 75

Figure 5 is a perspective view of the other section of the spreader. 80

Figure 6 is a disassembled perspective view of an adjustment bolt used in connection with the device, and

Figure 7 is a vertical transverse sectional view of the device, taken on the line 7—7 of Figure 1. 85

Referring to the drawings, in detail, in which like reference characters designate corresponding parts throughout the several views, there is shown a cement or concrete wall 10, which may be reinforced or not, the same being poured in the usual way between the false walls or sides 11 and 12 of the usual concrete mold or form used in the construction and erection of concrete buildings of any form, being of iron, wood or other material. The collapsible extension spreader constituting the subject matter of the present invention is designed to be placed between said walls for the purpose of keeping them uniformly spaced apart, plumb and straight, and with much less work than in connection with the present methods. 90

The device consists of a plurality of sections 13, 14 and 15, the former sections 13 and 14 being pivotally connected to form an articulated section or member collectively and the section 14 thereof being slidably or adjustably connected with the other section 15 and adapted to be held in fixed or rigid relation with respect thereto. The section 13 consists of a flat bar of suitable thickness having one end directed upwardly as indicated at 16 and apertured as indicated at 17 or otherwise formed for connection with a wire or other cable 18 adapted to be extend- 100

105

110

ed over a suitable beam or other part of the wall structure, either permanently or temporarily for the purpose of exerting upward pull thereon by a downward pull on the 5 cable or wire in the act of collapsing the spreader as will be hereinafter more particularly set forth. The other end of the bar forming the section 13 which may be of metal, 10 wood, or other material, though preferably the former, is of right angular cross section being most desirably, a section of angle iron having a vertical portion or web 19 and a top portion or horizontal web 20, said portions forming vertical and horizontal flanges 15 at the free end of the articulated member and the section 13 thereof.

The top portion or web 20 forms a wall extending a portion of the length of the section 13, preferably a minor portion thereof 20 and forming an abutment wall or shoulder 21 at the inner end thereof, while the free end of the section 13 is formed with an end wall 22 extending at right angles to the bar 14 and perpendicular to the top wall 20 so as 25 to engage the inner face of one of the walls of the mold or form. The section 14 is also preferably of angle iron and the vertical web or flange 23 thereof is rounded off at the lower corner and outer end, as indicated at 30 24 and pivotally connected with the vertical web or bar of the section 13 against which it is disposed, as shown at 25. The pivot may be of suitable form and is shown in the form 35 of a headed rivet pivotally connecting the sections to permit relative movement thereof whereby the collapsing function is accomplished, facilitated by the rounded portion 24. The end wall 26 of the section 14 produces a shoulder or abutment designed to 40 engage the shoulder 21 when the sections of the articulated member are disposed in alignment to render the same rigid, when the upper edge of the bar 13 will be aligned with the upper face of the section 14.

45 The opposite end of the section 14 is provided in the vertical web thereof with an aperture 27 designed to receive a bolt 28 horizontally therethrough, the threaded shank of the bolt being engaged by a winged 50 nut 29 and the head 30 thereof having preferably, a poly sided or polygonal outline, preferably hexagonal and having one corner thereof cut off as shown at 31, to provide a flat portion for a purpose to be subsequently 55 explained, while the lower portion presents a corner or point 32 adapted to be used as an indicating member in the adjustment of the spreader as will also be explained hereinafter.

60 The section 15 is also preferably produced of angle iron and the horizontal web 33 narrowed to fit beneath the horizontal web 34 of the section 14, while the vertical flange or web 35 of the section 15 is provided with a 65 longitudinal slot 36 parallel to the longitu-

dinal edges of said section and extending substantially throughout the length thereof. The walls of the slot 36 are provided at suitable spaced points, preferably equi-distantly spaced apart, with notches or semi-circular 70 seats 37 in the opposed walls thereof so as to form convenient rest places for the shank of the bolt 28 which latter is first engaged through the slot 36 with the head thereof disposed against the inner face of the web 75 35 beneath the web 33 of the section 15 and then through the aperture 27, the nut 29 being subsequently engaged thereon and serving when loosened, to permit longitudinal adjustment of the sections 14 and 15 or extension of the section 15 with respect to the 80 section 14 in order to vary the length of the spreader for use with walls of different thicknesses. In this position, the flattened portion 31 will seat against the bottom face 85 of the web 33 and the corner or point 32 serves as an indicator to register with a suitable mark or indentation 38 in the inner face of the web 35 beneath the recesses 37 so as to indicate when the adjustment has been made 90 to the prescribed or standard size so that uniformity of adjustment in the wall construction is insured. That is, the engagement of the flat portion 31 with the bottom face of the web 33 prevents turning of the 95 bolt or clamping member so that the point 32 will always be directed downwardly or adjacent to the indentations, while at the same time permitting the nut to be tightened when the sections 14 and 15 are secured in 100 any particular adjustment, according to the length desired. It is of course understood that the section 15 will slide with respect to the section 14, the coacting webs preventing the sections from pivoting one with respect 105 to the other and holding them rigid, in connection with the fact that the aperture 27 is spaced from the inner end of the section 14 and thus prevents upward movement of the section 15 on the pivot at that end, by engagement with the end of the web 34, thus 110 preventing the inner end of the section 15 from swinging downwardly, as it is thought will be clearly understood.

The free end of the bolt shank 28 may be 115 provided with a notch 39 to facilitate the tightening of the nut or retention of the bolt while tightening the nut.

The outer end of the web 33 of the section 15 is enlarged in width relative to the 120 inner portion which is disposed beneath the web 34 and said end is directed upwardly as shown at 40 and bifurcated or slotted as indicated at 41 to form a prong or fork, the furcations of which are designed to be straddled by the head of a nail or the like 42 which is driven into the adjacent wall or channel of the mold, in order to secure the spreader in position for use. The vertical web 35 of the section 15 is bent at right an- 125 130

gles beneath the end 40 to form an end wall 43 which is designed to engage the wall 12 in conjunction with the portion 40 as shown in the drawings. The end wall 43 comprises 5 the upper portion of the web 35 at the outer end thereof, and the lower end is disposed to project in the plane of the web 35 lengthwise of the spreader or sections thereof and is tapered to produce a spur 44 which is 10 forced into the wall of the mold to initially hold the same and cooperate with the nail or other fastening means 42 above referred to in 15 retaining the device in position.

In use, the device is applied as just described, the articulated member being in a collapsed position or open with the section 13 swung on the pivot 25 of the section 14 to the position shown in dotted lines in Figure 1 of the drawings. The device having been 20 disposed between the walls of the mold above the cement or base of the wall, the section 13 at the inner end thereof is pressed downwardly so that the device will be in an extended position, adjustment having been 25 previously accomplished to make the spreader of the required length. In this fashion, the end wall 22 will be brought into engagement with the other wall of the mold, being shown engaged with the walls 11 and 12 30 in the construction illustrated, and the sections 13 and 14 will be disposed in alignment, thus producing a rigid brace between the walls of the mold, so that the latter will be held uniformly spaced apart and thereby 35 insure uniformity in the thickness of the walls, thus produced. In this way, the building of concrete structures or walls will be greatly facilitated and the same will be kept plumb and straight, the faces thereof being 40 parallel or otherwise related as desired. It is of course to be understood that when the cement is poured to a height adjacent to the spreader, the latter is removed and reapplied, any number of the devices being employed 45 in practical use. It will also be obvious within the scope and spirit of the invention that the device may be employed in connection with ditches or channels dug in the earth or for other similar purposes, without departing from the construction or spirit 50 of the invention, as defined by the claims to be hereinafter presented.

In view of the foregoing it is thought that the operation of the device will be readily understood and in view of the simplicity and practical value, that it will readily command itself to those skilled in the art.

What is claimed is:—

1. A spreader of the class described comprising a bar section having an upwardly curved apertured end and a top wall provided with a transverse abutment shoulder, an end wall at one end of the bar to engage an element to be braced, a section pivoted adjacent one end to said bar in juxtaposition

to the shoulder and having a transverse end wall designed to abut said transverse shoulder at the top, the opposite end of the second section being apertured, a third section slidably fitting against the second section in 70 fixed alignment therewith and having an end wall at the opposite end of the spreader, a clamping bolt engaged through said aperture, and means whereby the third section is adapted to be engaged by said bolt, at a 75 plurality of points for extension thereof and holding the same in adjusted position.

2. A spreader of the class described comprising a bar section having an upwardly curved apertured end and a top wall provided with a transverse abutment shoulder, an end wall at one end of the bar to engage an element to be braced, a section pivoted adjacent one end to said bar in juxtaposition to the shoulder and having a transverse end wall designed to abut said shoulder at the top, the end of the second section being apertured, a third section slidably fitting the second section in fixed 80 alignment therewith and having an end wall at the opposite end of the spreader, a clamping bolt engaged through said aperture, and means whereby the third section is adapted to be engaged by said bolt, said third section being slotted longitudinally in alignment 85 with the second section, said bolt engaging said slot, and a nut on the bolt to frictionally clamp the second and third sections in 90 fixed relation.

3. A spreader of the class described comprising a bar section having an upwardly curved apertured end and a top wall provided with a transverse abutment shoulder, an end wall at one end of the bar to engage an element to be braced, a section pivoted adjacent one end to said bar in juxtaposition to the shoulder and having a transverse end wall designed to abut said shoulder at the top, the end of the second section being apertured, a third section slidably fitting the second section in fixed alignment therewith and having an end wall at the opposite end of the spreader, a clamping bolt engaged through said aperture, and means whereby the third section is adapted to be engaged by said bolt, said third section being slotted longitudinally in alignment with the second section, said bolt engaging said slot, the walls 100 of said slot being provided with a plurality 105 of open bolt rests, the head of the bolt engaging beneath the top wall of the third section and held against turning thereby, a nut engaged on the bolt for clamping the sections together in adjusted position, and means carried by the bolt and said slotted section for indicating the position of adjustment and said rests.

4. A spreader of the class described comprising a bar section having an upwardly curved apertured end and a top wall pro- 110 115 120 125 130

vided with a transverse abutment shoulder, an end wall at one end of the bar to engage an element to be braced, a section pivoted adjacent one end to said bar in juxtaposition to the shoulder and having a transverse end wall designed to abut said shoulder at the top, the end of the second section being apertured, a third section slidably fitting against the second section in parallel alignment therewith and having a bifurcated end wall at its outer end, a clamping bolt engaged through said aperture, and means whereby the third section is adapted to be engaged by said bolt, said third section being slotted longitudinally in alignment with the second section, said bolt engaging said slot, the walls of said slot being provided with a plurality of open bolt rests, the head of the bolt engaging beneath the third section and held against turning thereby, a nut engaged on the bolt for clamping the sections together in adjusted position, said third section beneath said bolt rests being provided with indentations, the top of the bolt head being flattened to engage the top of the third section and the bottom portion thereof being pointed for cooperation with the indentations to indicate the position of adjustment, and means at the outer end of the third section for securing the device in position.

5. A collapsible and adjustable extension spreader for concrete walls and the like comprising an articulated member comprising pivoted sections, said sections being of inverted L shape in cross-section and one section being pivoted at its outer end to a point spaced from the inner end of the other section, said sections having transverse cooperating means to limit the movement thereof into alignment when collapsed, means for moving one of said sections on the pivot relative to the other section, and another member slidably and adjustably connected to the inner section of the first-named member, said second member being also of inverted L shape in cross section and interfitting telescopically with the section to which it is connected.

50. 6. A collapsible and adjustable extension spreader for concrete walls and the like comprising an articulated member comprising pivoted sections, said sections being of inverted L shape cross section and one section being pivoted at its outer end to a point spaced from the inner end of the other section, said sections having transverse cooperating and abutting means to limit the movement thereof into alignment when collapsed,

means for moving one of said sections on the pivot relative to the other section, and another member slidably and adjustably connected to the inner section of the first named member, said second member being of inverted L shape cross section and interfitting telescopically with the section to which it is connected, and wall engaging means at the ends of the outer sections.

7. A collapsible and adjustable extension spreader for concrete walls and the like comprising an articulated member comprising pivoted sections, said sections being of inverted L shape cross section and one section being pivoted at its outer end to a point spaced from the inner end of the other section, said sections having transverse cooperating and abutting means to limit the movement thereof into alignment when collapsed, means for moving one of said sections on the pivot relative to the other section, and another member slidably and adjustably connected to the inner section of the first named member, said second member having end walls to engage elements to be retained in fixed relation and braced apart to prevent collapsing or movement thereof one toward the other, and means for securing uniform and standard adjustments of the second member with respect to the first member.

8. A collapsible and adjustable extension spreader for concrete walls and the like comprising an articulated member comprising pivoted sections, said sections being of inverted L shape cross section and one section being pivoted at its inner end to a point spaced from the outer end of the other section, said sections having transverse cooperating and abutting means to limit the movement thereof into alignment when collapsed, means for moving one of said sections on the pivot relative to the other section, and another member slidably and adjustably connected to the inner section of the first named member, said second member and said first named member having vertical end walls to engage elements to be retained in fixed relation and braced apart to prevent collapsing or movement thereof one toward the other, said second member having one end directed upwardly and slotted to form a fork for receiving a securing means in spanning relation with respect to the spaced portions thereof, and a spur projecting from said end to initially retain the device in position by engagement with one of said elements.

HORACE THOMPSON SWASEY.
